UNITED STATES PATENT OFFICE.

ALEXANDER WINTON AND HAROLD B. ANDERSON, OF CLEVELAND, OHIO.

SELF-STARTER FOR EXPLOSION-ENGINES.

1,171,292.

Specification of Letters Patent.

Patented Feb. 8, 1916.

Application filed July 5, 1912. Serial No. 707,934.

To all whom it may concern:

Be it known that we, ALEXANDER WINTON and HAROLD B. ANDERSON, citizens of the United States, residing at Cleveland, in the county of Cuyahoga and State of Ohio, have invented certain new and useful Improvements in Self-Starters for Explosion-Engines, of which the following is a specification, reference being had therein to the accompanying drawing.

This invention relates to improvements in self-starters for explosion engines, and is particularly adapted for and intended to be used in connection with explosion engines of automobiles, though it is capable of such use in connection with marine and stationary engines.

The present improvement is constructed and designed particularly for use in multiple cylinder explosion engines, and the present improvement relates to a type or form of self-starters for explosion engines in which the respective cylinders and pistons are utilized in succession to cause the pistons of the other cylinders to successively charge themselves with an explosive mixture containing acetylene gas, thus causing the cylinders to produce a continuance of the sequence of the motor functions and cause the said acetylene explosive mixture to be fired while the motor is in motion. This type or form of self-starter has the advantage of repeated chances for firing in the sequence of the motor operations to the extent of the capacity of the means for causing the respective cylinders and pistons to produce the sequence of the motor functions.

Heretofore there have been two types of self-starters for explosion engines, in which an explosive mixture containing acetylene have been utilized. One type is that in which the acetylene explosive mixture is caused to pass successively to each engine cylinder and charging them with said mixture while the engine is at rest. The engine is then started by causing an explosion in one only of the said cylinders by an ignition spark therein and has become known in the trade as "starting on the spark." In this type of self-starter the spark occurs in only one cylinder and while the engine is at rest, and there is, therefore, but the once chance for causing the starting explosion, and if this fails, the operation of charging the cylinder with acetylene gas while the engine is at rest must be repeated

until conditions are such that the spark in the starting cylinder will ignite the charge therein. Also in this type of self-starter a sudden explosion impulse is imparted to the engine while it is at rest and there is, of course, considerable inertia resistance and an equal degree of shock or strain on the mechanism which receives the explosion impulse while the parts are at rest. The other type of self-starters for explosion engines which utilizes a mixture containing acetylene gas for starting purposes is, that in which after the explosion impulses of the engine are cut off and it is running from its momentum, acetylene gas is admitted to the carburetor inlet manifold and one or more of the said cylinders thus charged before the engine is stopped, and is expected to remain in the said cylinder, or cylinders, until it is desired to again start the engine. The engine is then started "on the spark" as in the first type of self-starters herein described, and it has the mode of operation, and but the one chance of starting, and being subject of explosion impact while the engine is at rest, as explained in connection with the first described type heretofore known.

The improvement herein differs from either of these previously known types of self-starters in that means is provided for causing the engine to perform its sequence of operative functions, and while performing these functions the cylinders are caused to successively charge themselves with the acetylene explosive mixture repeatedly and in the sequence of motor functions, ignition is caused to occur successively in the said cylinders, thus repeatedly charging and sparking within the said cylinders until the explosive charge is fired, when the engine then picks up its own sequence of explosion functions from the carburetor and ignites independently of the starting mechanism in the usual manner. This difference, therefore, gives repeated chances of causing the engine to take up its own sequence of explosions, and also causes such explosions to occur while the engine mechanism is in motion, which does not subject the parts to explosion impulses of impact while the parts are at rest with the consequent disadvantages.

In the accompanying drawings: Figure 1 is a diagrammatic view showing the new type of self-starters for explosion engines.

Fig. 2 is an enlarged detached view, showing a modification in the manner of placing the acetylene tank in communication with the engine inlet manifold. Fig. 3 is a similar view showing another modification of the same mechanism.

In carrying out the inventive idea in producing this new type of self-starter and as an expression thereof, the drawings therein illustrate means whereby the cylinders are successively utilized as means for causing the engine to produce its sequence of functions.

Fig. 1 is a diagrammatic view in which 1 represents a plural cylinder engine. A pressure tank 2 is provided and this tank contains air or products of combustion under compression, which preferably is charged by the engine while it is performing its explosion functions, either in the well-known manner of an air-pump (not shown) operated by the engine, or by taking a part of the compressed products of combustion from one or more of the cylinders and conveying it to the tank 2 in the manner herein shown, and which is the preferred way of charging the tank 2. In this instance the tank is charged by taking part of the compressed products of combustion from two of the cylinders through the pipes 3 to a pipe 4, which connects with a short pipe 5, and thence through a pipe 6 to the pressure tank 2. A distributing valve 7 is operatively connected with the engine and so timed that communication is established through the said valve successively to the respective cylinders 1, through the pipes 8. Communication between the tank 2 and the distributing valve 7 is effected through the pipes 5, 6, and 9, and this communication is controlled by a manually operated valve 10, which may be constructed to be operated either by hand or the foot.

Acetylene gas is contained in a tank 11, and is in communication with the carbureter inlet manifold 12 of the engine through the pipes 13 and 14. A valve 15 is located at the junction of these pipes 13 and 14 and by means of this valve the flow of the acetylene gas to the said manifold 12 is permitted or cut off. If desired, a gas pressure regulator may be placed in the communication between the tank 11 and the manifold 12, as shown in Fig. 3, to which reference will be hereinafter made for the purpose of controlling the pressure at which the gas is admitted to the said manifold.

It is, of course, to be understood that the old and well-known mechanism of an explosion engine is not shown or attempted to be shown in the diagrammatic view Fig. 1, such as the igniting mechanism, as well as the other mechanisms of the well-known type of explosion engines, for these are so well-known and understood that an illustration thereof or description would only serve to

unnecessarily encumber the drawings and description.

The operation of my new type of self-starter is illustrated in Fig. 1 and is this: The engine being at rest the operator, by means of the valve 10, establishes communication between the pressure tank 2 and the distributing valve 7. The communication between the acetylene tank 11 and the inlet manifold 12 is obtained. The distributing valve 7 admits the pressure to that cylinder which is on the explosion stroke and this cylinder is thus utilized to set the motor in motion and to cause that cylinder which is on its charging stroke to charge itself with the acetylene explosive mixture through the inlet manifold. In the operation of the engine, the distributing valve 7 admits the pressure to the cylinders on their explosion strokes in succession and thus cause the cylinders on their charging stroke to charge themselves with the acetylene explosive mixture in succession, and also cause the ignition spark in succession in the respective cylinders in the manner well understood. From this it will be observed that the cylinders are utilized in succession as a means for setting and keeping in motion the parts of the engine while other cylinders are in succession, thereby caused to charge themselves with the acetylene explosive mixture, whereby should the explosive charge in one or more of the cylinders thus first charged fail to explode by reason of the condition of the mixture, the cycle of the engine is continued, the cylinders on the explosion stroke cause other cylinders to be charged with the explosive mixture until it is in proper condition to and does explode and the explosion-engine will then pick up its own sequence of explosion functions and operate independently of the starting mechanism. It will be observed from this, as explained in the first part of this description, that this is a type of self-starters utilizing acetylene explosive mixture essentially different from the devices heretofore used and known. The advantage of using an acetylene explosive mixture is well-known, in that a far greater variation in the mixture of this gas in the explosive mixture can occur without destroying its combustible nature than with other kinds of gases, thus making it desirable to be used, provided it can be simply and efficiently accomplished.

It is understood, of course, that when the engine picks up its sequence of explosion functions the operator closes or permits the valve 10 to close and also closes the acetylene controlling valve 15. This arrangement will be very efficient in cold weather, because the acetylene can be used for running the engine a suitable length of time to heat the parts so that a proper carburation of the gasolene will take place through the carbureter. The

engine while running then recharges the pressure tank 2. It will also be understood that in this type of self-starters the repeated charging of the cylinders with the acetylene mixture and causing the igniting spark within the cylinders is limited only to the capacity of the compression tank 2. Since in this type of self-starters the charging and igniting operations are repeated in the regular functions of the engine, and since the more readily ignitable acetylene explosive mixture is used, it is found in practice that this type of starter is absolutely reliable under all conditions, and irrespective of climatic conditions. It is not dependent upon a single or repeated efforts in the same cylinder in which the conditions are likely to be substantially unchanged.

In Fig. 2 a modification is shown in which the valve or button 10' when operated to start the engine to functioning will cause an acetylene controlling valve 15' to be opened and permit the gas to flow to the manifold 12, at the same time that the engine is put in motion. This is effected by providing a projecting valve stem 16 with an arm 17 located in the path of travel of the valve or button 10' so that when the valve or button 10 is moved to open the valve it engages the arm 17 and opens the valve 15'. Preferably any suitable form of gas pressure regulator may be used between the acetylene tank 11 and the manifold 12, preferably located between the valve which controls the flow of acetylene and the tank. This is conveniently shown in Fig. 2 at 18.

In Fig. 3 another modification is shown for controlling the flow of the acetylene to the manifold 12, which consists in providing the pipe 9' which communicates with the distributing valve 7 with a laterally projecting conduit or pipe 9", which is in communication with the pipe 9'. In communication with the pipe 9" is a casing 20 which contains a flexible diaphragm 21, and this diaphragm is connected with the stem 22 of the acetylene controlling valve 23. Preferably a spring 24 serves to hold the valve 23 to its seat and also acts upon the diaphragm 21, as clearly shown. When the valve 10' is open to permit pressure from the tank 2 to the distributor 7, pressure is also admitted to the casing 20 and acts on the diaphragm 21, forcing it to one side and opening the valve 23, thus permitting the acetylene to flow through the pipes 14 and 13 to the manifold 12. The valve 23 also has a projecting stem 25 of a diameter equal to the valve 23, and this stem 25 projects outward through a stuffing box 26; whereby it is capable of operation from the outside and whereby the valve and its stem may be re-

moved by removing the stuffing box. Preferably a second spring 27 is placed in the stuffing box and acts upon the valve through its stem to cause it to be seated. By means of this construction the valve is capable of operation from the outside in the event it should stick or fail to operate. In this pipe is also a pressure or gas regulator 18, as is shown in Fig. 2.

Having thus described the invention, what is claimed and desired to be secured by Letters Patent is:

1. The combination with a plural cylinder explosion engine, of an acetylene gas supply in communication with the engine cylinders on their charging stroke, means acting upon the piston of one of said cylinders when the engine is at rest and adapted to successively act upon the pistons of the other cylinders in the sequence of the motor functions by acting on the firing stroke, a controlling member for the acetylene gas supply and a controlling member for the said piston actuating means, the latter controlling the acetylene controlling member.

2. The combination with a plural cylinder explosion engine, of an acetylene gas supply in communication with the engine cylinders on their charging stroke, means acting upon the piston of one of said cylinders to set the engine in motion and adapted to act successively on the pistons of the other cylinders to continue said motion in the sequence of the motor functions by acting on the firing stroke, a controller for the said actuating means, a controller for the acetylene supply, said controllers operatively connected, whereby when the actuating means controller is operated the acetylene controller is correspondingly operated.

3. The combination with a plural cylinder explosion engine, of an acetylene gas supply in communication with the engine cylinder on its charging stroke, air means acting upon the piston of one of said cylinders when the engine is at rest and adapted to successively act upon the pistons of the other cylinders in the sequence of the motor function by acting on the firing stroke, a controlling member for the acetylene gas supply, and a controlling member for the air actuating means, the latter controlling the acetylene controlling member.

In testimony whereof we hereunto affix our signatures in the presence of two witnesses.

ALEXANDER WINTON.
HAROLD B. ANDERSON.
